UNITED STATES PATENT OFFICE.

JOHN WOOD, OF BROOKLYN, NEW YORK.

IMPROVED SUBMARINE ARMAMENT.

Specification forming part of Letters Patent No. 13,062, dated June 7, 1864.

To all whom it may concern:

Be it known that I, JOHN WOOD, of Brooklyn, in the county of Kings and State of New York, have invented, made, and applied to use a certain new and useful Means of Firing Cannon Below the Water-Line; and I do hereby declare the following to be a full, clear, and exact description of the said invention, reference being had to the annexed drawings, making part of this specification, wherein—

Figure 1 is a plan of my improvement, and Fig. 2 is an elevation of the same as fitted into a vessel.

Similar letters designate the same parts.

The nature of my said invention consists in a means for preventing the ingress of water through a tube both before and after a projectile from a cannon is fired through that tube, the object being to allow for firing below the water-level at an adjacent vessel, so as to injure her below that water-line where least protected, and where injury would be the most detrimental to an enemy.

In the drawings, *a* represents a portion of a vessel's outline, which vessel may be of any desired size or shape and of any suitable material.

b represents a cannon that is to be mounted on any suitable swivel or carriage, and is to be located in the vessel at or below the water-line; and I remark that more than one gun may be provided in a vessel, together with the tube and apparatus for passing the ball and keeping out water, or one gun may be so located as to be fired through either one of three or more such tubes passing through the bow or stern and sides, so as to direct the projectile to the desired point.

I will proceed to describe the construction and operation of one of said tubes fitted with my improvements.

c is a tube passing through the vessel and securely fitted in place. *d* is a slide-valve, actuated by screws, ropes, or other convenient means, so that it can be drawn up or closed down to keep water out of the tube, and *e* is a similar valve for the same purpose, at the rear part of the said tube, to be used if necessary, and a third similar valve, or a hanging one, might be applied to the end of the pipe *c*, outside the vessel, as an additional security.

f is a pipe extending up from the tube *c* above the water-line, and said pipe might also

be provided with a valve or stop-cock if required.

I make use of two or more sliding plates, *g g*, of felt, rubber, sheet metal, or other suitable material possessing sufficient strength to resist the pressure of water, and sliding freely up into chambers or through openings in the upper part of the tube *c*.

When the gun is to be fired, it is to be drawn back or swung around and loaded as usual, and it may be slid forward so that its muzzle enters within the tube *c*, the parts fitting each other, or some little space may be left between the end of the tube and said muzzle. The gates *d* and *e* are to be raised and all the slides *g*, except one, as represented in Fig. 2. The other slides *g* are to be sustained by ropes or latches, so that they can be easily and instantly dropped. The gunner stands ready with the connection to the suspended slide or slides *g* in one hand, and the moment he fires he drops such slide or slides *g* into place across the tube *c*. The projectile going out of the tube before either of the suspended gates could fall penetrates or carries with it the slide that had kept the water out, and the other slide or slides, falling instantly behind, close the pipe *c* before much or any water has time to run back. This may be repeated several times in succession, the apparatus being provided with the necessary number of slides, or new ones may be introduced in place of those shot away. The pipe *f* allows the air, gases, and smoke freely to escape, and prevents said air forming a cushion for the ball or the smoke passing out between decks. A pump, well, or other receptacle for such water as may leak or pass into the tube is to be provided at *h* to receive the same, from which well the water is to be pumped out by any usual means. The tube *c* is represented as projecting beyond the vessel and containing two slides or gates, *i i*. These may be operated by chains outside the vessel and close the tube more securely. If desired, several slides or gates *g*, may be fitted into a plate, as represented in Fig. 3, that can be set over an opening in the top of the pipe *c* and bolted to place, each gate being made of a thin sheet of metal or rubber set in a frame. The frames of the gates remain and keep the pipe tight after the sheet has been shot through, and the next frame in the rear is to be dropped in succession as the cannon

is fired, and then by closing the gate *d* the plate may be removed with the frames and new slides or gates fitted into place.

I do not claim firing under water; neither do I claim a single diaphragm through which the ball passes; but

What I claim, and desire to secure by Letters Patent, is—

A horizontal pipe provided with the air-escape pipe and a series of slides containing

sheets of metal or other material, and fitted so that said slides can be dropped in succession, as specified.

In witness whereof I have hereunto set my signature this 22d day of March, 1864.

JOHN WOOD.
